UNITED STATES PATENT OFFICE.

THEODORE H. NYE, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

GUIDE FOR ROLLING-MILLS.

972,219.

Specification of Letters Patent. Patented Oct. 11, 1910.

Application filed April 30, 1908. Serial No. 430,074.

To all whom it may concern:

Be it known that I, THEODORE H. NYE, a citizen of the United States, residing at Worcester, in the county of Worcester and 5 Commonwealth of Massachusetts, have invented a new and useful Improvement in Guides for Rolling-Mills, of which the following is a specification, accompanied by drawings forming a part of the same, in 10 which—

Figure 1 represents a front elevation of a rolling mill housing provided with a guide embodying my invention. Fig. 2 is a sectional view of my improved guide on a 15 larger scale, and shown on the plane of the broken line 2—2, Fig. 1.

Similar reference letters and figures refer to similar parts in the different views.

The object of my present invention is to 20 provide an improved mode of attachment for rolling mill guides which will secure maximum rigidity and also facilitate their application to and removal from a rolling mill housing, and it consists in the construction and arrangement of parts as hereinafter described and pointed out in the annexed claims.

Referring to the accompanying drawings 1, 1, denote the housings and 2, 2, a pair of 30 rolls journaled therein.

3 denotes the guide supported on a bar 4 attached to the front of the housings by bolts 5, 5, and vertically adjustable by means of slots 6, 6. The guide 3 may be used either 35 with or without guide plates, a pair of which, in the present instance, are shown at 7 and 8. The bar 4 extends across the housing and is provided on its upper side with the longitudinal bearing surfaces 9 and 10 40 upon which the guide rests, and along which it is horizontally adjustable to bring it in alinement with the circumferential grooves or passes 11 of the rolls. The guide 3 is provided at its outer end with a downwardly 45 projecting apron 12, provided at its lower end with a slot 13 for the reception of a bolt 14, having a head 15 horizontally adjustable along a T-shaped slot 16, having a central opening 17 on its upper side to 50 allow the bolt 14 to be inserted in the slot. The upper surface of the guide bar 4 is also provided with an undercut or dovetailed shoulder 18 to receive a corresponding dovetailed shoulder 19 formed on the under side 55 of the guide.

When the guide is placed in position, with the dove-tailed shoulders 18 and 19 engaging each other, as shown in Fig. 2, and with the bolt 14 inserted, the nut 20 is tightened sufficiently to prevent the disengagement of 60 the dovetailed shoulders 18 and 19, thereby holding the guide rigidly in position for use. By loosening the nut 20 slightly, the guide may be horizontally adjusted on the bar 4, or the slotted apron 12 may be lifted 65 off the bolt 14, and the guide removed.

In case the metal moving through the rolls becomes accidentally impeded, forming what is known as a "cobble," the strains upon the guide will become sufficient to lift it from 70 its attachment to the bar 4, thereby preventing the destruction of the guide, or the bolt 14 may be made sufficiently weak to allow it to break under any unusual strain applied to the guide, the object being to allow the 75 guide to be displaced whenever a cobble is formed, thereby preserving the guide and facilitating the removal of the cobble. The guide is held by a single nut 20 on the front of the apron 12 and in convenient position to be reached by an attendant, rendering it an extremely easy matter to either attach or remove the guide or adjust it as desired upon the bar 4. Any lifting strain exerted upon the guide will be positively resisted by the 80 dovetailed shoulders 18 and 19, which are held in engagement by the longitudinal strain resisted by the bolt 14 and also by the frictional contact between the nut 20 and the apron 12. If the frictional resistance 85 between the nut 20 and the apron 12, or the tensile strength of the bolt 14 is less than the accidental lifting strain imparted to the 90 guide, the latter will be raised from its seat.

On the right hand side of the rails in Fig. 2 I have shown a guide 21 which is used without any guiding plates, but is provided with a method of attachment to the guide bar 22, as already shown and described with 100 reference to the guide 3, being provided with an apron 23, having a slot 24 to receive a bolt 25, having a head 26 and a nut 27, by which the dovetailed shoulder 28 of the 105 guide is held in engagement with a corresponding dovetailed shoulder 29 on the bar 22.

As the metal moves through the guide in a plane at considerable distance above its attachment to the bar 4, resistance to the passage of metal therethrough will produce 110

torque. By holding the end of the guide next the rolls by the interlocking dovetailed surfaces 18 and 19, located in a vertical plane as far as practicable behind the vertical plane of the attachment by the apron 5 12 and bolt 14, enables the guide to be held in place by a comparatively light apron and a small bolt.

I claim,

- 10 1. A rolling mill housing having a guide supporting bar, a guide mounted thereon, said guide and said bar provided with re-entrant engaging surfaces to hold said guide from vertical movement, and means for holding said surfaces in engagement by a strain toward the rolls of the rolling mill.
- 15 2. A rolling mill housing having a guide supporting bar, a guide mounted thereon, said guide and said bar provided with re-entrant engaging surfaces to hold said guide from vertical movement, and a bolt parallel 20 with the longitudinal axis of said guide for holding said surfaces in engagement.
- 25 3. A rolling mill housing having a guide supporting bar, a guide mounted thereon, said guide and said bar provided with re-entrant engaging surfaces for holding said guide from vertical movement, but arranged to allow horizontal movement away from the 30 rolls of the rolling mill, said bar having a slot parallel with said surfaces, said guide having a depending flange outside of said bar, and a bolt held in said slot and passing through said flange arranged to draw said 35 guide toward the rolls of the rolling mill.
4. The combination with a rolling mill housing and rolls journaled therein, of a guide bar and a guide mounted on said bar, reentrant engaging surfaces between said

guide and said bar near the end of said 40 guide next said rolls, with the surface on said guide outside of the surface on said bar, and means parallel with the longitudinal axis of said guide at or near the opposite end of the guide for holding said surfaces in 45 engagement by a strain toward said rolls.

5. A rolling mill housing having a guide supporting bar, a guide mounted thereon, said guide and said bar provided with re-entrant engaging surfaces arranged to hold 50 said guide from vertical movement, but to allow horizontal movement of said guide in a direction away from the rolls of the rolling mill, and means for holding said surfaces in engagement.

6. A rolling mill housing having a guide supporting bar, a guide mounted thereon, said supporting bar and said guide provided with reentrant engaging surfaces, whereby the inner end of said guide is held from 60 vertical movement, and means attached to said bar for frictionally holding the outer end of said guide from vertical movement.

7. A rolling mill housing having a guide supporting bar, a guide mounted thereon, 65 said supporting bar and said guide provided with reentrant engaging surfaces, whereby the inner end of said guide is held from vertical movement, and a bolt held in said bar and in frictional contact with said guide, arranged to draw said surfaces into engagement and to hold the outer end of said guide from vertical movement.

Dated this 28th day of April 1908.

THEODORE H. NYE.
